UNITED STATES PATENT OFFICE.

LESLEY B. IRVIN, OF HENAGAR, ALABAMA.

TRACE-CONNECTOR.

1,014,709.

Specification of Letters Patent.

Patented Jan. 16, 1912.

Application filed April 11, 1911. Serial No. 620,338.

To all whom it may concern:

Be it known that I, LESLEY B. IRVIN, a citizen of the United States of America, and resident of Henagar, Alabama, have invented 5 certain new and useful Improvements in Trace-Connectors, of which the following is a specification.

This invention relates to whiffle trees and particularly to a device for connecting a 10 trace to a swing tree for retaining the same against accidental displacement or dislodgment, novel means being provided, associated with the whiffle tree to effect the objects stated.

15 With the foregoing and other objects in view, the invention consists in the details of construction and in the arrangement and combination of parts to be hereinafter more fully set forth and claimed.

20 In describing the invention in detail, reference will be had to the accompanying drawings forming part of this specification wherein like characters denote corresponding parts in the several views, and in 25 which—

Figure 1 illustrates a perspective view of a fragment of a plow beam and a fragment of a whiffle tree connected thereto; Fig. 2 illustrates a fragment of a whiffle tree; Fig. 30 3 illustrates a longitudinal sectional view of a fragment of the whiffle tree.

The whiffle tree 11 has a connection 9, a fragment of which is shown which may be of any construction for attaching it to a 35 plow, a vehicle or the like, said whiffle tree comprising a rolled metal body doubled on itself as at 12, with the sides lying parallel and being provided with a pivotal pin 13 on which a trace engaging wheel is mounted, 40 the said wheel rotating between the sides of the whiffle tree. The end of the whiffle tree is provided with a notch 15 of such depth as to accommodate a ring 16 or other connection from a trace 17. The wheel is 45 provided with radially depressed slots 18 with laterally extending passages 19 communicating therewith, the said passages terminating in seats 20 for the rings 16.

In the operation of the device the wheel is 50 rotated until the radially disposed slot is in alinement and merges with the notch 15

in which position the ring is free to enter the slot 18 and notch 15 in which latter position the wheel is free to be rotated leaving the ring seated in the notch. Rotation of the 55 wheel causes that part of the wheel having the passages to travel past the ring thus bringing the seat 20 into alinement with the said ring. The seats 20 are free or outside of the zone of the end and sides of the 60 whiffle tree and the said ring may, therefore, be drawn out of the notch 15 into the seat 20 after which the wheel may be partially rotated to the position shown in Fig. 1, thereby preventing dislodgment of the ring 65 from the wheel. The passage 19 between the seat and the radial slot is in alinement with the edge of the whiffle tree so that the said passages are virtually closed and prevent the dislodgment of the ring from the seat after 70 the wheel has been partially rotated from the position where the radial slots are in alinement with the notch. The ring 16 can, therefore, only be removed from the seat by returning the radial slot 18 into alinement with the notch 15 and restoring the 75 said ring to the notch 15 while said movement is taking place.

As shown in the drawings there are four seats 20 on the wheel, two on each side of 80 each of the radial slots and therefore slight manipulation of the wheel is necessary to effect an engagement or disengagement of the trace connection therewith.

I claim—

85 In a whiffle tree, a body having separated parallel sides, a wheel mounted between the sides near the end thereof, the end of the said body having notches, the said wheel having radial slots, lateral passages merging with the slots, and seats merging with the passages, the said passages being in such position from the center of the wheel as to be guarded by the whiffle tree except at the notched portion of said whiffle tree. 95

In testimony whereof, I affix my signature in the presence of two witnesses.

LESLEY B. IRVIN.
